(57) **CLAIM**

The ornamental design for a toy car, as shown and described.

DESCRIPTION

FIG. 1 is a perspective view showing our new toy car design; FIG. 2 is a front view thereof;

FIG. 3 is a rear view thereof;

FIG. 4 is a right side view thereof;

FIG. 5 is a left side view thereof;

FIG. 6 is a top thereof; and,

FIG. 7 is a bottom view thereof.

The broken lines depict portions of the toy car that form no part of the claimed design.
